IRVING S. MERRELL AND OLIVER EDWARD MERRELL, OF SYRACUSE, NEW YORK,
ASSIGNORS TO MERRELL-SOULE COMPANY, OF SYRACUSE, NEW YORK, A CORPOR-
ATION OF NEW YORK.

SPRAYING-NOZZLE.

1,183,393.

Specification of Letters Patent. Patented May 16, 1916.

Application filed February 16, 1912. Serial No. 678,116.

To all whom it may concern:

Be it known that we, IRVING S. MERRELL and OLIVER EDWARD MERRELL, of Syracuse, in the county of Onondaga, in the State of New York, have invented new and useful Improvements in Spraying-Nozzles, of which the following, taken in connection with the accompanying drawings, is a full, clear, and exact description.

10 This invention has relation to pressure spray nozzles, particularly used for the purpose of converting organic substances containing moisture and having a high viscosity, such as condensed milk and eggs, into

15 a dry powder.

Particularly, the invention consists in such a pressure spray nozzle especially designed for ejecting a material, such as condensed milk or eggs, into a current of heated air, in accordance with the method set forth in the United States Letters Patent to Stauf, No. 666,711, January 29, 1901.

In the present commercial practice of the Stauf invention the milk, eggs or blood, is ejected into a current of heated air through a minute discharge orifice of the spray nozzle at a high pressure, a pressure in excess of two thousand (2,000) pounds per square inch being employed. In the case of 20 the spray nozzles which have heretofore been employed, the discharge of the spray at the high velocity due to the pressure into the current of heated air tends to create a partial vacuum in the vicinity of the exterior 25 of the nozzle on its discharge face and particles of the sprayed liquid collect on the discharge face of the nozzle surrounding the discharge orifice so that a layer of the sprayed material forms thereupon, in a moist condition. This collected material, being 30 immediately in the path of the heated air, is baked into a crust and is injuriously affected by the heat to which it is continuously subjected, and particles, being blown off from 35 time to time, as the mass accumulates, mingle with the properly dried powder and affect the quality thereof.

One important object of the present invention is to so construct the nozzle as to 40 prevent this accumulation of the sprayed material.

We have found, by long experience and practice that in order to obtain the best results, in desiccating a highly viscous material, such as condensed milk, the liquid

should be converted into an exceedingly fine mist by the spraying nozzle, and that the mist should be widely diffused within the drying chamber in order to insure immediate and thorough evaporation by bringing 60 it into intimate contact with a large volume of the heated air current. It is important that the particles of this mist should be as nearly uniform in size as possible and that these particles be distributed as uniformly 65 as possible through the heated air current. This insures the thorough and rapid drying of every particle with the greatest possible economy of heat and power. In order to obtain these results a whirling movement is 70 imparted to the liquid within the spraying device and a high pressure is employed. This produces a fine uniform spray or mist which whirls at high velocity as it emerges from the spraying device and is thus caused to diffuse 75 widely and mix intimately and uniformly with the air current. A high pressure must be used to make the spray uniformly fine and to discharge it at a high velocity and in sufficient quantity through the minute discharge orifice employed to render the process 80 commercially practicable.

The desiccating chamber may be of reasonable limits, for the sprayed liquid is converted into a dry powder before coming in 85 contact with any of the walls of the chamber, as the result of the diffusion and rapid drying of the sprayed particles.

A nozzle embodying the present invention is illustrated in the accompanying drawings, 90 wherein—

Figure 1 is a side view of the nozzle, a portion of its ejecting end being broken away to illustrate the character of the discharge passage or ajutage. Fig. 2 is a face 95 view of the discharge end of the nozzle. Fig. 3 is a longitudinal section. Fig. 4 illustrates the spray disk showing the same in edge view (partly in section) and also in front view. Fig. 5 illustrates the body 100 of the nozzle, showing a side view partly in section thereof and also a rear view thereof. Fig. 6 illustrates the plug which closes the rotary chamber of the nozzle at the rear, this figure including a rear view and a side 105 view of the plug. Fig. 7 is a plan view of the strainer and its supporting ring or sleeve. Figs. 8 and 9 are detail sectional views illustrating by arrows the course of the milk or other similar liquid under treat- 110

ment. Figs. 3 to 7, inclusive, are on a scale double that of Figs. 1 and 2, and Figs. 8 and 9, are on a scale four times that of Figs. 3 to 7.

5 Structurally, the nozzle comprises a body A, a cap B, a casing C, a spray disk D, a plug E, a plug pin F, a screen G, a screen supporting ring or sleeve H, and a washer I.

The casing C, is interiorly screw threaded 10 at a, to receive at its rear end a liquid conveying pipe J, shown in Fig. 1. Forward of the screw threaded end a, the casing is enlarged constituting an interior chamber b, which is interiorly screw threaded at its 15 rear end to receive the exteriorly screw threaded sleeve H, to the rear face of which the screen G, is attached by soldering or in an equivalent manner. The front end of the sleeve H, is notched as indicated at c, to facilitate insertion and withdrawal. The body 20 A, has a flange d, at its outer end, which is supported against the outer end of the casing C, the washer I, being interposed. The body is maintained in place liquid tight by 25 the cap B, which screws on to the exterior of the casing C, and forces the flange of the body tightly against the washer I.

The body A, has a liquid whirling chamber K, at the middle of its outer side to 30 which the liquid is conveyed by two ducts L, L, which communicate at their outer ends with the chamber b, of the casing C.

The rear end of the whirling chamber K, is closed by the plug pin F, held in place 35 by the plug E, which screws into a socket e, at the rear of the body A.

The spray disk D, has a minute central orifice M, connecting with the whirling chamber K, and through which the liquid 40 is discharged in a fine spray.

The ajutage O, on the cap B, is outwardly flaring conical or évasé, and its central axis is in line with the center of spray orifice M, and with the central longitudinal line of the whirling chamber K.

Assuming that milk is the liquid to be sprayed, it is forced under heavy hydraulic pressure, say two thousand pounds per square inch or greater, through the feed pipe 50 J, through the screen G, into the interior chamber b; thence through the ducts L, L, into the whirling chamber K; and thence outwardly through the spray orifice M, and the évasé ajutage O, into the current of heated air.

The effective action of the spray nozzle is largely dependent upon the proper proportions of its various parts.

The nozzle which is illustrated in the 60 drawings is particularly designed for spraying milk in the production of milk powder, and its proportions are proper for that purpose when milk is sprayed under high pressure.

65 The dimensions of the illustrated nozzle

can be judged by specifying certain of the measurements. The interior diameter of the chamber b, is one and three-sixteenths (1.1875) inches. The spray orifice may be of different dimensions, that illustrated being made by a drill two hundred and sixty-five ten thousandths (.0265) of an inch in diameter. In actual practice, this orifice is sometimes made smaller, as by a drill as small as one-eightieth (0.125) of an inch in diameter. Intermediate sizes can be employed. The plug pin F, is less than one-tenth of an inch in diameter, being .0895 of an inch in diameter and it makes a close fit within the whirling chamber K. The outer end of the whirling chamber K, and the inner face of the spray disk D, are concave, the radius of the circle of concavity on the inner face of the spray disk being .0365 of an inch. As shown in Fig. 9, by reason of these concavities, the whirling chamber K, at the rounded discharge end has a smooth concave wall for directing the whirling liquid to the spray orifice M. The conical wall of the évasé ajutage O, makes an angle of thirty-one and one-half (31.5) degrees to the axis thereof; and the external front face P, of the cap B, is likewise conical and the angle of this cone to the axis of the ajutage is fifty-three and one-fourth (53.25) degrees. These angles are those which experience demonstrates will prevent the deposit of the sprayed milk on the exterior faces of the nozzle when sprayed at high pressure into a current of heated air. The inclination of the face P, is opposite to that of the ajutage.

At its outer or discharge end, the spray orifice M, is flared or coned in conformity with the coning of the ajutage so as to provide a smooth continuous surface for the liquid in passing from the minor diameter of the orifice to the ajutage. The drill measurement heretofore stated for the orifice is that which determines the diameter thereof, at its cylindrical smallest place. The spray disk is .036 of an inch in thickness. Each of the ducts L, is made by a drill of the diameter of .0265 of an inch. Each of these ducts L, is at an angle of twenty-five (25) degrees to a plane perpendicular to the axis of the whirling chamber, as indicated in Fig. 9. The ducts L, enter the whirling chamber at its bottom just in front of the outer end of the plug pin F. As shown in Fig. 8, the two ducts L, are not in line with each other nor in line with the central axis of the whirling chamber, but are respectively offset to opposite sides of said axis. These two ducts are made by drills entering in opposite directions and where these drills pass each other at the axis of the whirling chamber there is a space of one one-hundredth (.01) of an inch between their nearest faces. Accordingly, the two opposite streams of milk entering the whirling chamber

ber (circular in cross-section) at high velocity set the milk into rapid rotation and since the restricted portion of the spray orifice is of very small extent along the line 5 of the axis of the whirling chamber, this whirling movement continues in the discharge spray. The screen is of one hundred to the inch wire mesh and it prevents the passage of any solids which might clog the 10 ducts L, and the spray orifice M.

All of the parts are readily detached and reassembled to facilitate cleaning the nozzle and in making repairs.

All parts are made of brass, with the exception of the plug pin F, and washer I, the latter being preferably made of hardened steel, readily detachable from the plug E. The whirling of the milk in the whirling chamber K, rapidly bores a hole in the 20 end of a brass pin. Accordingly, a pin of hardened steel is desirable. The washer I, is preferably made of lead.

All of the surfaces with which the liquid may come in contact after entering the 25 mouths of the ducts L, are highly polished; and both faces of the spray disk are highly polished as well as the faces of the cap and body which meet the spray disk, thereby making the spray joints liquid tight.

30 We claim—

1. A high pressure spray nozzle having in combination a body portion with a whirling chamber and ducts leading thereto, a cap having an évasé ajutage, a removable spray 35 disk interposed between the cap and body portion and having a minute discharge orifice between the whirling chamber and said ajutage, and a casing secured to the cap and having a chamber surrounding the 40 rear part of the body portion.

2. A high pressure spray nozzle having in combination a body portion having a whirling chamber and ducts leading thereto, a spray disk removably secured between the 45 cap and body portion and having a minute discharge orifice leading from the whirling chamber, a cap having an opening registering with said discharge orifice, and a casing connected to the cap, said casing and cap 50 operably related to hold the body portion in proper relative position.

3. A high pressure spray nozzle having in combination a body portion having a whirling chamber, substantially circular in cross 55 section and concave at its outer end, and ducts leading thereto, a spray disk removably secured between the cap and body portion and having a minute discharge orifice leading from the whirling chamber, a cap having an opening registering with said discharge orifice, and a casing connected to the 60 cap, said casing and cap operably related to hold the body portion in proper relative position.

65 4. A high pressure spray nozzle having in

combination a body portion having a whirling chamber and two oppositely inclined feed ducts entering the bottom of said whirling chamber out of line with each other and offset to one side of the axis of said chamber, the two ducts entering said chamber at opposite sides of said axis, a spray disk removably secured between the cap and body portion and having a minute discharge orifice leading from the whirling chamber, a 70 cap having an opening registering with said discharge orifice, and a casing connected to the cap, said casing and cap operably related to hold the body portion in proper relative position. 75

5. A high pressure spray nozzle having in combination a body portion having a whirling chamber, substantially circular in cross section and concave at its outer end, and two oppositely inclined feed ducts entering the 80 bottom of said whirling chamber out of line with each other and offset to one side of the axis of said chamber, the two ducts entering said chamber at opposite sides of said axis, a spray disk removably secured between the 85 cap and body portion and having a minute discharge orifice leading from the whirling chamber, a cap having an opening registering with said discharge orifice, and a casing connected to the cap, said casing and cap operably related to hold the body portion in proper relative position. 90

6. A high pressure spray nozzle having in combination a body portion having a whirling chamber circular in cross section and 100 with a concave outer end and a discharge orifice at the center of its outer end, a plug adjustably related to said body portion and having a hardened plug pin closing the inner end of said whirling chamber, a spray 105 disk removably secured between the cap and body portion and having a minute orifice registering with the discharge orifice of the whirling chamber, and means for holding the spray disk in operable position. 110

7. A high pressure spray nozzle having in combination a body portion having an opening therethrough, a portion of said opening internally threaded, a screw plug engaged with said portion and provided with a plug pin fitting said opening tightly and adapted to form a removable bottom for a substantially cylindrical unobstructed whirling chamber, said screw plug having a laterally extending flange at its rear portion of 120 greater diameter than the internally threaded portion of said body and adapted to contact with said body portion to limit the relative movement of said parts in one direction, a removable spray disk having a minute orifice communicating with said whirling chamber, a cap holding said spray disk in proper relative position to said body portion, and an inlet to said whirling chamber. 125

8. A spray nozzle comprising a body por- 130

tion having a whirling chamber circular in cross section and concave at its outer end, a recess in the outer face of said body portion, a spray disk seated in said recess and having an orifice leading to the whirling chamber, said orifice cylindrical at its smallest dimension, concave at its inner end and forming a continuation of said whirling chamber, and flaring at its outer end and 10 ducts leading to said whirling chamber.

9. A spray nozzle comprising a body portion having a whirling chamber circular in cross section and concave at its outer end, and having a removable hardened plug 15 forming the bottom wall thereof, a recess in the outer face of said body portion, a spray disk seated in said recess and having an orifice leading to the whirling chamber, said orifice cylindrical at its smallest dimension, 20 concave at its inner end and forming a continuation of said whirling chamber and flaring at its outer end, inclined ducts discharging across said chamber at opposite sides of an axis thereof, and a cap holding said spray 25 disk seated in the recess in the outer face of said body portion and having an évasé ajutage forming a continuation of the flaring outer end of the spray disk orifice.

10. A spray nozzle comprising a body portion having a whirling chamber, a duct leading to said chamber, a cap having an évasé ajutage, a thin spray disk removably secured between the cap and body portion and having its opposite faces lying throughout 35 substantially their entire area in contact with the body portion and cap respectively, said disk having a minute orifice forming means of communication between the whirling chamber and the évasé ajutage in said 40 cap.

11. A spray nozzle comprising a body portion having a whirling chamber, a duct leading to said chamber, a cap having an évasé ajutage, a thin spray disk removably secured between the cap and body portion and having its opposite faces lying throughout substantially their entire area in contact with the body portion and cap respectively, said disk having a minute orifice forming means of communication be- 45 50

tween the whirling chamber and the évasé ajutage in said cap, the wall of said orifice being the only portion of said disk exposed in the whirling chamber.

12. A spray nozzle comprising a body portion and a cap having an ajutage, one of said elements having a recess formed in the face adjacent the other element, a thin spray disk in said recess and having its opposite faces throughout substantially their entire 55 area in contact with the body portion and the cap respectively, a whirling chamber in said body, inclined ducts leading to said chamber, said spray disk having a minute orifice forming means of communication between the ajutage through the cap and the 60 whirling chamber.

13. A high pressure spray nozzle having in combination a body portion provided with a whirling chamber circular in cross section 70 and substantially eight hundred and ninety-five ten-thousandths (.0895) of an inch in diameter, a cap having an évasé ajutage, the wall of which is inclined to the axis of the ajutage approximately thirty-one and 75 five-tenths degrees (31.5°), and an external face inclined in the opposite direction approximately fifty-three and twenty-five one-hundredths (53.25) degrees to the axis of the ajutage, a removable spray disk interposed between the cap and body portion and having an orifice approximately two hundred and sixty-five ten-thousandths (.0265) 80 of an inch, or less, in diameter, a casing secured to the cap and having a chamber, 85 ducts leading from said chamber to the whirling chamber, said ducts approximately two hundred and sixty-five ten-thousandths (.0265) of an inch in diameter and inclined to a plane perpendicular to the axis of the 90 whirling chamber approximately twenty-five (25) degrees.

In witness whereof we have hereunto set our hands this 14th day of February, 1912.
